FUEL PUMPING AND METERING DEVICE

Carl Beckman, Detroit, Mich.

Application January 21, 1935, Serial No. 2,719

3 Claims. (Cl. 103—87)

The present invention pertains to a novel fuel pumping and metering device for supplying liquid fuel to oil burners.

The primary object of the present invention is to provide positive acting means for pumping liquid fuel from a main reservoir to burners located remote from the reservoir and means for regulating the amount of fuel supplied to the burners. An advantage of positive pumping means, as compared with the gravity flow of the fuel commonly used, is that the tank may be placed remote from the burners and in a plane lower than the burners. Such an arrangement permits the tank to be placed underground or in the basement of a dwelling and thereby reduces the fire hazard.

Another object of the invention is to provide means in a device of this character for maintaining a constant level of liquid fuel in a position where it will flow by force of gravity to the burners where it is to be consumed, the level of fuel maintained at a definite point without the use of float valves such as are ordinarily used in this type of device. In this connection the invention provides a novel overflow through which excess fuel is removed from the device and returned to the supply reservoir.

Another object of the present invention is to provide a metering device including a motor for operating a fuel pump and valves for regulating the flow of fuel from the device to burners, the motor being electrically operated and the valves having means operated simultaneously therewith for controlling the motor supply circuit so that the motor is caused to operate simultaneously with the opening of a valve and the motor remains inoperative when the metering valves are closed.

With the above and other ends in view the invention is fully disclosed by way of example in the accompanying drawing, in which

Figure 1 is a vertical cross section;

Figs. 2, 3 and 4 are cross sections taken respectively on lines 2—2, 3—3 and 4—4 of Fig. 1, and

Fig. 5 is a cross section taken on lines 5—5 of Fig. 3.

Reference is had to the drawing by characters which are employed to designate corresponding parts throughout.

The device comprises a housing 1 formed with a cylindrical chamber 2 in which is mounted a screen 3, the latter being secured in place by movable elements 4 and a disk 5, the latter also serving to seal the open end of the chamber 2.

A port 6 is provided in the housing 1 and opens into the chamber 2, the port 6 being adapted to be connected to a fuel supply tank (not shown) by suitable piping. Above the chamber 2 the housing 1 is formed with a second chamber 7 and a head 8 is secured on top of the housing 1 to close the chamber 7. The head 8 is formed of insulation.

In the chamber 7 is provided a gear pump comprised of gears 9 and 10 and an operating shaft 11 connected by a universally flexible element 12 to a drive shaft 13 of a motor 14. The motor 14 is secured on the head 8 by tie bolts 15 which engage in screw threaded bores 16 in the housing 1. The tie bolts thus serve to hold the motor 14 and head 8 on the housing 1.

The gear pump has an inlet port 17 extending from the chamber 2 and an outlet port 18 extending into chamber 7. It is obvious, therefore, that fuel may enter the port 6 and be pumped through the chamber 2 and screen 3 into the chamber 7. In order to prevent the pump from filling the chamber 7 above a predetermined level or, in other words, to cause an overflow of fuel, there is provided an overflow tube 19 whose outlet end 20 is adapted to be connected to the supply tank or to a receptacle for receiving the overflow.

Opening through the bottom wall of the housing are outlet ports 21 and 22, each having one end opening into the chamber 7 and their other ends screwthreaded to receive pipes (not shown) which lead to oil burners. In the ports 21 and 22 are secured valve fittings 23 and 24, each having a valve seat 25 and a metering port 26. Screwthreaded into the fittings 23 and 24 are valve elements 27 and 28, each having a conical part 28a adapted to cooperate with the valve seats 25, and with cylindrical parts 29 cooperating with the metering ports 26. The valves 27 and 28 have operating handles 30 and 31 respectively by means of which manual pressure may be applied thereto for the purpose of rotating the same. Springs 43 are sleeved on the valves 27 and 28 between the handles 30 and 31 and the head 8 to offer resistance against rotation of the valves so that vibration in the device will not move the valves.

The electrical circuit to the motor 14 includes a wire lead 32 which is directly connected to the motor winding. The other wire lead 33 is connected to a terminal post 34 mounted in the head 8. A second terminal post 35 is mounted in the head 8 spaced apart from the terminal 34 and is connected to the motor winding by a wire 36.

lead 36. A flexible conductor 37 has one end secured to the terminal 34 and has its free end 38 projecting beyond the terminal 35 and in the absence of external pressure the conductor 37 5 engages the terminal 35 to serve as means for bridging the two terminals. A flexible conductor 39 is secured at one end to the terminal 35 and has its free end 40 projecting beyond the terminal 34. Conductor 39 normally serves as means 10 for bridging terminals 34 and 35. Carried by the handles 30 and 31 are downwardly projecting pins 41 and 42 formed of insulating material. Shoulders 44 are provided in the head 8 for limiting the movement of the pins 41 and 42. 15 Assuming that the lead wires are connected to a supply source of electrical energy and the two conductors 37 and 39 are in the position shown in Fig. 5, an electrical circuit is completed through the terminals 34 and 35 and conductors 37 and 39 which causes the motor 14 to operate. The gear pump is thus operated and fuel is pumped into the chamber 7 and a constant level, equal to the height of the overflow tube 19 is maintained in the chamber 7. In 20 the event that the valves 27 and 28 are moved to their closed position illustrated in Fig. 3, the handles 30 and 31 will be rotated so that the pin 41 strikes the end 40 of conductor 39 and causes the same to flex away from the terminal 34. Pin 42 will likewise engage the end 38 of conductor 37 and will flex the same to move it out of contact with terminal 35. In their flexed condition the conductors 37 and 39 no longer bridge the terminals 34 and 35 and the current 25 is interrupted at this point. However, should either one of the valves be moved toward an open position the pins 41 or 42, as the case may be, must pass through the position shown in Fig. 5, in which case the conductor 37 or 39 moved 30 thereby will close the circuit by contacting the other terminal. In other words, when either or both valves are not entirely closed the motor circuit is completed.

In connection with the valves it will be seen 45 with reference more particularly to Fig. 3, that the conical parts 28a are adapted to engage the seats 25 to seal the fittings 23 and 24 against passage of fluid therethrough. By moving the valves longitudinally the cylindrical parts 29 50 gradually pass the openings 26 and thus provide for adjustment of the effective area thereof. In other words, the cross sectional area of the fuel passage may be regulated to provide for metering of the fuel and the valve mechanism may be 55 adjusted to seal the device against discharge of fuel, this latter function being performed by means auxiliary to the metering parts.

Although a specific embodiment of the present invention has been illustrated and described it will be understood that various changes may be made within the scope of the appended claims without departing from the spirit of the invention, and such changes are contemplated. 5

What I claim is:

1. In a device of the character described, a housing having a liquid reservoir, a pump in said housing for supplying liquid to said reservoir, 10 metering valves in the bottom wall of said housing, actuating means for said valves disposed externally of said housing, an electric motor supported by said housing externally thereof and connected to said pump, circuit controlling means 15 adjacent to said valve actuating means, and means on said valve actuating means for actuating said circuit controlling means.

2. In a device of the character described, a housing having an open top and a bottom wall 20 formed with a chamber, a port opening into said chamber and adapted to be connected to a supply source, a pump on said bottom wall having an intake communicating with said chamber and an outlet opening into the interior of said housing, 25 an outlet port in said bottom wall separate from said chamber, a valve fitting in communication with said outlet port, said valve fitting having an inlet port therein spaced above the plane of said bottom wall, an overflow tube extending from 30 said bottom wall to a plane above the plane of said valve fitting port, a closure for the open end of said housing, and a motor supported on said closure by means engaging said bottom wall in such manner as to retain said closure on said 35 housing, said motor being operatively connected to said pump.

3. In a device of the character described, a housing having an open top and a bottom wall formed with a chamber, a port opening into said 40 chamber and adapted to be connected to a supply source, a pump on said bottom wall having an intake communicating with said chamber and an outlet opening into the interior of said housing, an outlet port in said bottom wall separate 45 from said chamber, a valve fitting in communication with said outlet port, said valve fitting having an inlet port therein spaced above the plane of said bottom wall, an overflow tube extending from said bottom wall to a plane above 50 the plane of said valve fitting port, a closure for the open end of said housing, and a motor supported on said closure by means engaging said bottom wall in such manner as to retain said closure on said housing, and a flexible connection between said motor and pump. 55

CARL BECKMAN.
